[57] CLAIM

The ornamental design for a hose nozzle, as shown and described.

DESCRIPTION

FIG. 1 is a top plan view of a hose nozzle embodying our new design;

FIG. 2 is a left side elevational view thereof;

FIG. 3 is a bottom plan view thereof;

FIG. 4 is a rear end elevational view thereof;

FIG. 5 is a right side elevational view thereof;

FIG. 6 is a front end elevational view thereof;

FIG. 7 is another top plan view thereof showing the hose nozzle in an adjusted position;

FIG. 8 is a top plan view of a modified form of the hose nozzle shown in FIG. 1;

FIG. 9 is a left side elevational view of FIG. 8;

FIG. 10 is a bottom plan view of FIG. 8;

FIG. 11 is a rear elevational view of FIG. 8;

FIG. 12 is a right side elevational view of FIG. 8;

FIG. 13 is a front elevational view of FIG. 8; and

FIG. 14 is another top plan view of FIG. 8 showing the hose nozzle in an adjusted position.

FIG. 2

FIG. 1

FIG. 4

FIG. 3

FIG. 5

FIG. 6

FIG. 12

FIG. 13

FIG. 14
